CLAIM

We claim the ornamental design for a motorcycle fender, as shown and described.

DESCRIPTION

FIG. 1 is a left elevation view of a motorcycle fender showing our new design;

FIG. 2 is a right elevation view thereof;

FIG. 3 is a bottom plan view thereof;

FIG. 4 is a top plan view thereof;

FIG. 5 is a rear elevation view thereof;

FIG. 6 is a front elevation view thereof;

FIG. 7 is a top, rear and left side perspective view thereof; and,

FIG. 8 is a bottom, front and left side perspective view thereof.

The broken lines in the drawings illustrate portions of the motorcycle fender that form no part of the claimed design.

1 Claim, 8 Drawing Sheets
